(57) **CLAIM**

The ornamental design for an exercise strap, as shown and described.

DESCRIPTION

FIG. 1 is a front perspective view of the exercise strap showing my new design;

FIG. 2 is a front elevation view thereof;

FIG. 3 is a rear elevation view thereof;

FIG. 4 is a left side elevation view thereof, the right side elevation view being an identical image thereof;

FIG. 5 is a top plan view thereof, the bottom plan view being a mirror image thereof;

FIG. 6 is an enlarged detail front elevation view indicated by line 6-6 of FIG. 2;

FIG. 7 is an enlarged detail rear elevation view indicated by line 7-7 of FIG. 3;

FIG. 8 is an enlarged front elevation view of the repeating stitch pattern of the exercise strap indicated by line 8-8 of FIG. 6; and,

FIG. 9 is an enlarged rear elevation view of the repeating stitch pattern of the exercise strap indicated by line 9-9 of FIG. 7.

The thin short broken lines forming a rectangle in FIG. 3 define the bounds of the claimed design and form no part thereof.

The thick elongated dashed lines forming rectangles in FIGS. 1-3 and 6-7 and the thick diagonal elongated dashed lines within these rectangles in FIGS. 1-3 indicate stitching lines and are distinguishable from the thin weight broken lines in FIG. 3, and form part of the claimed design.

The thin elongated dashes of FIGS. 2-3 indicate the appearance of a cooperating hook and loop fastener, and form part of the claimed design.

The dash dot dash lines of FIGS. 6-9 illustrate the enlarged view of the figures and form no part of the claim.
